CAMOUFLAGE MATERIAL

Rudolf G. Rüter, Köln-Deutz, Germany; Hildegard Rüter, Friederike E. Benisch, Brigitte R. von Gierke, and Rotraud E. Barner, heirs of said Rudolf G. Rüter, deceased

Filed Nov. 13, 1958, Ser. No. 773,770
Claims priority, application Germany Nov. 18, 1957
5 Claims. (Cl. 41—10)

This invention relates to a system of camouflaging particularly for military use.

The well-known camouflage nets consisting of cord netting or fishnets garnished with colored strips, etc. are easily recognized due to their flat 2-dimensional surface. According to another known camouflage method many linear slits are cut into a sheet, the slits being disposed alternating in parallel rows. Pulling out the sheet in a direction transverse to the slits produces a mesh-like arrangement of the material with a plurality of interstices. Due to the warping of the sheet the portions between the slits are somewhat distorted out of the plane of the sheet. According to this known system the distortion is so little that additional strips must be attached to the sheet in order to produce a desired 3-dimensional camouflaging effect. But this is a rather detailed and expensive procedure.

According to the present invention there is provided a 2-dimensional sheet of textile or plastics which can be easily transformed into a real 3-dimensional structure without any additional material and work, by providing numerous nonlinear, preferably shaped or semi-circular cuts are made in the sheet and then distending the sheet. The ends of the cuts protrude into the interior of the corresponding bow-shaped cuts. The deeper the cuts reach or extend into the adjacent bows, the higher the leaf-like lappets or lips are lifted out of the plane of the sheet and the more the sheet may be drawn out. In order to simulate structure as near as possible to natural foliage, the bow-cuts are preferably made in different sizes and may be irregularly disposed in various directions. Thus expanding the sheet in length and width effectuates a pell-mell or non-uniform structure of quite irregularly drilled straps, outstanding leaf-tips and numerous holes of different sizes, so that the camouflage material looks like a wall of vine foliage.

Further objects will be apparent from the following description when considered in connection with the accompanying drawing in which:

FIGURE 1 is a plan view of a section of a camouflage sheet showing a regular pattern of cuts in the sheet,

FIGURE 2 is a plan view of the camouflage sheet with contrasting zones of light and color reflections and in extended shape,

FIGURE 3 is a plan view of a sheet showing a pattern of cuts in more or less irregular fashion,

FIGURE 4 is a plan view of the sheet of FIG. 1 shown extended to effect the third dimensional configuration, and

FIGURE 5 is a cross section through the sheet of FIG. 4 taken on line 4—4.

Within the scope of this invention it is possible to adapt the camouflaged objects to their various surroundings with regard to structure, general brightness and color tone. Due to the possibility of inclining the leaf-like lappets to the plane by pulling out the sheet, the structure of the camouflage material may be varied in numerous steps, so that it may be changed from a rather flat to a totally projected surface. As the lappets by this stretching are gradually replaced by small or large dark-looking holes, the general brightness of the camouflage set may be made to melt into the environment. In a similar manner

2

the color tone of the foliage may be changed by painting the lappets in a bright green shade while the straps are painted dark olive. Thus a little pull on the sheet will produce a rather bright and a further pull will produce a dark greenish appearance of the covered object. The color adaptation to the surroundings may be completed by painting for example, green color on the lappets disposed in one direction and brown for instance on the transversely aligned lappets. Such pull on the sheet as to 10 length, transforms the total color to a greenish hue, while a pull in the breadth direction will produce a brownish tone. Finally, if the back of the sheet is colored white the camouflage cover may be used not only during the winter but it will protect the concealed object from the 15 thermic nuclear radiation of an atomic bomb.

According to the invention the sheets from which the foliage is made, are preferably supposed to consist of a nonmelting and nonburning tissue or, at least of a texture of polyamides (nylon), the surface of which is covered 20 with a layer of polyvinylchloride in order to prevent the burning and melting of the plastic. As such, the camouflage foliage is extremely light and economical of space when stored and during transport, and while the weight is not raised by moisture, soldiers will be able to conceal 25 the objects within a very short time.

The foliage or sheet according to the invention may be used for covering the helmet and the body of a soldier, for draping over weapons, for concealing ditches, foxholes etc. In connection with a carrier the foliage sheet may 30 be used for garnishing camouflage nets, tarpaulins, combat clothing and so on. In such a way it is possible to deceive the enemy by irregularly garnishing or covering a fishnet with a number of small and large pieces of pulled-out foliage in various patterns of ramified bushes or tree 35 tops. Due to the striking resemblance with natural vegetation any object which is covered with such a net will be totally concealed. Furthermore, the foliage may be employed in the form of cut strips which are interlaced between the meshes of a net, or wound around a weapon. 40 Another purpose and use of the invention is to change the tell-tale outlines of the objects by fastening elastic carriers, that is, steel wires to the top-edges of the objects carrying the artificial foliage sheets projecting out beyond the outlines like a cock's comb. In such a way not only the reconnoitering from the ground is rendered difficult, but the observation by air, with the shadows cast on the ground being broken up and resembling the shadows of harmless bushes or trees.

Referring now more specifically to the drawing FIG. 1 shows a portion of a sheet 6 of plastic, textile or any other suitable material having a plurality of U-shaped cuts 7 in the form of a regular series 8 and an inverted series 9 constituting a row 10. The U-shaped cuts 7 are so formed that there is a space 11 between rows of cuts 10 and when the sheet 6 is pulled in opposite directions as shown in FIG. 4, the sheet 6 will take on a third dimension in that the rounded portions 12 of each U-shaped cut will be pulled out of its plane to project at an angle relative to the sheet 6 with the extent of the angle dependent upon the length and extent of the pull.

FIG. 2 shows by contrast of the light and dark sections forming a foliage pattern with for instance the U-shaped cuts 13 made to follow a regular pattern and contrasted with the rounded portions 14. The sheet of FIG. 2 shows the sheet extended.

FIG. 3 shows a plurality of U-shaped cuts 16 made in the sheet 15 which may be uniform in length and width but which may be of irregular dimensions, some 17 longer than others 18. Also the U-shaped cut portions, in FIG. 3, do not follow any particular pattern such as the symmetrical row arrangement as illustrated in FIG. 1. The sheet of FIG. 3 may also be pulled from

opposite sides similar to FIG. 4 or it can be pulled both vertically as well as horizontally to produce varied effects in third dimension configuration.

It is of course possible to make the sheets of any textile material of cotton and any artificial fibers as well as canvas and even heavy paper and light cardboard. It is however preferable to make the sheets from any number of plastic materials of the proper thickness and color or colors.

The sheet may be pulled to any desired extent so that the angle of the portions 12 of each U-shaped cut may assume any desired angle relative to the plane of the sheet. Due to the size of the sheet and the nature of the material used, the sheet will maintain its stretched out position indefinitely while in use due to frictional contact and by means of fastening means if used.

I claim as my invention:

1. A camouflage device to simulate foliage comprising a sheet material with two dimensions and having a plurality of irregular U-shaped and curved cuts therein so formed over the length and breadth of the sheet that each cut will protrude into the curved portion of the adjacent cut, said sheet when pulled in a direction substantially parallel to the legs of the cuts, the U-shaped cuts will extend beyond the plane of the sheet.

2. A camouflage device according to claim 1, in which the cuts form lappets and the legs are painted in different colors to simulate leaves as to color.

3. A camouflage device according to claim 1, in which the sheet when pulled in opposite directions will extend beyond the plane of the sheet to comprise a third dimension by portions of the U-shaped cuts projecting at angles from the sheet.

5 4. A camouflage device according to claim 1, in which the ends of each U-shaped cut portion extend into and are disconnected from the adjacent curved portion of the U-shaped cut.

10 5. A camouflage material formed from a textile with two dimensions having a plurality of curved cuts over the length and breadth of said textile and interlocking with each other so that the ends of the cuts terminate within the fields defined by adjacent substantially oppositely disposed curved cuts, said camouflage appearing irregular with the cut out areas extending outside the plane of the fabric upon suspending the same.
